UNITED STATES PATENT OFFICE.

NORMAN B. HURD, OF NEW BRITAIN, CONNECTICUT, ASSIGNOR TO AMERICAN HARDWARE CORPORATION, OF NEW BRITAIN, CONNECTICUT, A CORPORATION OF CONNECTICUT.

LOCK AND LATCH.

Application filed October 4, 1922. Serial No. 592,235.

To all whom it may concern:

Be it known that I, NORMAN B. HURD, a citizen of the United States of America, residing at New Britain, Connecticut, have 5 invented a new and useful Improvement in Locks and Latches, of which the following is a specification.

My invention relates to improvements in locks and latches, the object being to greatly 10 simplify and cheapen the construction without sacrifice of strength or durability.

In the accompanying drawings,

Fig. 1 is a side view of the latch complete.

Fig. 2 is a section on the line 2-2 of 15 Fig. 1.

Fig. 3 is a view of the opposite side of the latch from that shown in Fig. 1.

Fig. 4 is a perspective view of a detail, 20 relatively enlarged.

1 is the side plate which constitutes the frame of the device. The edge of this plate 1 is bent at an angle to form the face plate 2. In the face plate is a passage for a latch bolt head 3. The head 3 is pressed forward-

25 ly by a coil spring 4 which surrounds the tail 5 of said latch bolt. In the form shown the extreme end of the tail 5 is laterally offset, as indicated at 5^a, to form a shoulder against which a latch retracting device may

30 operate. In the form shown this latch retracting device comprises a lever 6, pivoted at 7 to the plate 1. 8 is a spring which normally impels the lever 6 forwardly against an abutment 9 which may be struck

35 up from the plate 1 so as to stand at right angles thereto, as shown in Fig. 2. One side of the latch bolt head 3 is guided on the adjacent wall of the opening in the face plate 2 through which the latch bolt head

40 passes. The inner portion of the latch bolt head may be provided with an offset 3^a, which rides along the inside of the plate 1. In this manner the outer end of the latch bolt is guided and held in place. The inner end of the latch bolt, that is to say, the tail 5, is provided with a unique form of

45 guide in the form of a detachable plate 10, which has a passage therein through which the tail of the latch bolt passes and in which it may reciprocate. This plate 10 is provided

50 with angular ears 10^a-10^b, as shown in Figs. 2 and 4. Adjacent to the ears are notches 10^b-10^b. The plate 1 is provided with an opening of sufficient size to permit the ears 55 10^a to be passed therethrough from one side

to the other, and this opening has a lateral extension which is slightly narrower in width. The edges of the plate adjacent this narrower extension are adapted to the notches 10^b-10^b, so that when the plate 1 is moved into the position indicated in the drawings these edges will extend into said notches 10^a, whereby said plate 10 will be interlocked with the plate 1, as clearly seen in Figs. 2 and 3. The plate 10 may be supported against any tendency to tilt by the abutment 9. The spring 4 holds the plate snugly in place, while at the same time operating to project the latch bolt 3. By this very simple method of securing and guiding 60 the tail of the latch bolt the necessity for a cap or cover plate is entirely avoided, thereby simplifying greatly the construction and work of assembly, likewise reducing the amount of metal, all of which results in the 65 effecting of substantial economies.

If desired, the latch may be provided with a second latch-retracting device in the form of a handle 12, which is suitably mounted on the plate 1 and may be provided with a 70 roll-back hub 14, the end of which engages the shoulder 3^a of the latch bolt head, so that, by moving the handle 12, the latch bolt may be retracted. Obviously, any suitable 75 form of locking means to block the operation of either or both of the latch-retracting devices or the latch itself may be added, but I have not shown such devices herein, as they are too well known to require illustration.

90 Preferably, the plate 1 is provided with a longitudinal slot 15, the edges of which may be turned back, as shown, to form parallel guideways for the end 5^a of the latch bolt tail. To facilitate assembling the various 95 parts the inner side of the latch bolt head 3 may be beveled off, as indicated at 3^b (Fig. 2). Thus, in putting the parts together the spring 4 may first be slid over the latch bolt tail. The latch bolt tail may then be passed 100 through the opening in the face plate 2 from the outside. The plate 10 may then be slid onto the latch bolt tail, and the several parts may then be moved into a position which will permit the ears 10^a to be locked to the 105 plate 1.

110 It will be seen that the plate 10 comprises what may be called a detachable latch tail guide. The ease and convenience with which this guide may be interlocked with the single

frame plate of the device, or may be disengaged therefrom for repair or replacement, constitutes a substantial feature of improvement and is largely responsible for the objects accomplished.

5 I claim:

1. In a lock, a side plate, a face plate at one edge thereof, said face plate having a passage, a latch bolt mounted to move in 10 said passage, a separate guide for the tail of said latch bolt comprising a plate, with means for detachably interlocking said guide with said side plate and holding the same at an angle thereto, and a separate latch-retracting means.
- 15 2. In a latch, a side plate, a face plate at the edge thereof having a passage, a latch comprising a head and a tail, the head passing through said face plate passage, a separate guide for the latch bolt tail comprising a plate, with means for detachably interlocking said guide with said side plate and holding the same at an angle thereto, and a separate latch-retracting means.
- 20 3. In a latch, a side plate, a face plate at the edge thereof having a passage, a latch comprising a head and a tail, the head passing through and guided in said face plate passage, and a guide for the latch bolt tail comprising a plate, with means for detachably interlocking the same with said side plate at an angle thereto, said means including an angular ear formed integrally with said plate, said side plate having an 25 opening to permit said ear to be passed therethrough for engagement with the opposite surface of said side plate.
- 30 4. In a latch, a side plate, a face plate at the edge thereof having a passage, a latch comprising a head and a tail, the head passing through and guided in said face plate passage, and a guide for the latch bolt tail comprising a plate, with means for detachably interlocking the same to said side plate, and a separate latch-retracting means.
- 35 5. In a latch, a side plate, a face plate at the edge thereof having a passage, a latch comprising a head and a tail, the head passing through and guided in said face plate passage, and a guide for the latch bolt tail comprising a plate, with means for detachably interlocking the same to said side plate, and a separate latch-retracting means.
- 40 6. In a latch, a side plate, a face plate at the edge thereof having a passage, a latch comprising a head and a tail, the head passing through and guided in said face plate passage, and a guide for the latch bolt tail comprising a plate, with means for detachably interlocking the same to said side plate, and a separate latch-retracting means.

ing through and guided in said face plate passage, and a guide for the latch bolt tail comprising a plate, with means for detachably interlocking the same with said side plate at an angle thereto, said means including an angular ear formed integrally with said plate, said side plate having an opening to permit said ear to be passed therethrough for engagement with the opposite surface of said side plate, said guide plate being notched, a portion of said side plate extending into said notch to assist in interlocking when said parts are assembled.

5. In a latch, a side plate, a face plate at one edge thereof having a passage for a latch bolt, an integral lug abutment on said side plate to the rear of said passage in the face plate, a latch bolt comprising a head and a tail, the head being positioned in said passage, said lug acting as a back stop therefor, a detachable latch bolt guide for the tail of said bolt, with means for detachably interlocking the same to said side plate, and a separate latch-retracting means.

6. In a latch, a side plate, a face plate at one edge thereof having a passage for a latch bolt, a lug abutment on said side plate to the rear of said passage in the face plate, a latch bolt comprising a head and a tail, the head being positioned in said passage, said lug acting as a back stop therefor, and a detachable latch bolt guide for the tail of said bolt, with means for detachably interlocking the same to said side plate adjacent said abutment, and a spring for said latch bolt; said spring operating in one direction to project the bolt and in the opposite direction to hold the guide in its interlocked engagement with said side plate.

NORMAN B. HURD.
